UNITED STATES PATENT OFFICE.

WILLIAM H. WALDRON, OF NEW BRUNSWICK, NEW JERSEY.

BLOCK-PRINTING MACHINE.

1,159,301.

Specification of Letters Patent.

Patented Nov. 2, 1915.

Application filed February 27, 1915. Serial No. 19,941.

To all whom it may concern:

Be it known that I, WILLIAM H. WALDRON, a citizen of the United States, and a resident of New Brunswick, county of Middlesex, State of New Jersey, have invented certain Improvements in Block-Printing Machines, of which the following is a specification.

My invention relates to a type of block printing machine for printing material such as oil cloth, linoeum, and other fabrics, which are fed intermittently through a machine and in which there is a series of reciprocating block carriers which carry the printing blocks which make the impressions on the material as it is fed through the machine.

The object of my invention is to provide a mechanical means for automatically controlling the block carriers in order that any desired block can make an impression at any time, so that the machine can print bordered rugs, or mats, and similar floor or table coverings.

In the accompanying drawings:—Figure 1, is a side view of sufficient of a block printing machine to illustrate the reciprocating block carriers and the means for operating the same; Fig. 2, is a longitudinal sectional view on the line *a—a*, Fig. 3; Fig. 3, is a sectional plan view; Fig. 4, is a transverse sectional view on the line *b—b*, Fig. 1; Fig. 5, is an end view; Fig. 6, is a sectional plan view on the line *c—c*, Fig. 4; Fig. 7, is a sectional view on the line *d—d*, Fig. 6; Fig. 8, is a diagram view illustrating the three shafts; and Fig. 9, is a diagram illustrating the arrangement of the rods when three sets of three rods are used.

Referring to the drawings, 1 is the main frame of my improved block printing machine.

2, 2 are the reciprocating block carriers adapted to travel in guides 3 secured to the upper member of the frame 1.

4, 4 are the blocks, which are secured to the block carrier. The block carrier, in the present instance, consists of two vertical members 5 which are adapted to the guides 3 and a transverse member 6 which extends across the machine and to which the blocks 4 are directly secured.

7, 7 are the usual inking elements having wheels which travel on the rails 8. These

inking elements are connected together by 55 rods 9 and means are provided for reciprocating the rods longitudinally so that the rolls of the several inking elements will pass under the blocks 4 and will ink the projecting surfaces thereof, the rollers rotating in 60 the ink fountain in the usual manner.

10 is a transverse shaft on which is a cam 11 for reciprocating the carrier 2. Mounted on the carrier is a roller 12 which comes in contact with the cams, as illustrated in 65 Fig. 1.

13 is a hand operated latch, which is arranged to engage the portion 14 of the carrier and to hold it out of action. The latch can be locked in engagement with the carrier by a keeper 15. The shaft 10 is mounted in bearings 16 in the frame of the machine and a cam 11 is mounted on the shaft at each end thereof, as clearly illustrated in Fig. 4. Loosely mounted on the shaft is a 75 worm wheel 17, and 18 is a clutch head which is secured to the shaft and has a bolt 19 arranged to enter a cavity 20 in the hub of the worm wheel 17, Figs. 6 and 7. Back of the bolt is a coiled spring 21 which 80 tends to force the bolt out and into engagement with the worm wheel. The bolt has a pin 22 and the tapered end of the retractor 23 comes in contact with this pin to withdraw the bolt. The retractor is mounted on 85 one end of the rod 24 adapted to bearings 25 in the frame of the machine. Mounted on the rod 24, between a sleeve 26 thereon and one of the bearings 25, is a coiled spring 27, which tends to force the rod forward in 90 the direction of the clutch. Mounted on the rear end of the rod is an open frame 28 having a roller 29 which bears against the cam 30 on the cam shaft 31. The frame is guided in a bearing 32 secured to the main 95 frame 1 of the machine, as clearly shown in Fig. 2, so that, as the cam 30 rotates, a longitudinal motion will be imparted to the rod 24 and the retractor will be moved toward or from the clutch, so that the control 100 of any particular carrier is governed by its cam. In the present instance, there is a cam for each carrier.

In the drawings, I have illustrated three cams and three rods 24, 24^a and 24^b; the rods being bent to clear the mechanism, as required. The worm wheels 17 on the shafts 10 are driven by worms 33 on a longitudi-

nal shaft 34 mounted in bearings 35 driven in any suitable manner from the main driving elements of the machine.

The fabric, in the present instance, travels over a table 36, and endless conveying belts 37 having prongs 38 engage the edges of the fabric. These belts pass around drums 39 on a shaft 40 at each end of the machine. One of these shafts is a driven shaft 5 so that the driven mechanism is intermittent as in the ordinary machines of this type, so that the fabric moves a certain distance and then remains stationary during the time the printing blocks are making the impression.

10 The operation is as follows:—If the machine is provided with a number of carriers, each carrier is controlled by a cam and these cams are so arranged that, as they rotate, certain of the shafts 10 will be driven by 15 the main driving shaft through the worm gear, while others will be disconnected therefrom and will remain stationary. The cams 30 are so timed with respect to the cams 11 that the driving mechanism will be 20 disconnected only when the blocks are in the raised position, as illustrated in Fig. 1, and if it be desired to print a rug with a border and the length of the rug is equal to three 25 blocks, then the entire rug, if of one color, 30 can be printed with three blocks. If the rug is to be printed in two colors, six blocks will be necessary, each set of three supplying a given color. One block of each will have 35 the right hand border thereon and part of the body of the rug. Another block will have the left hand border and a portion of the body of the rug, and the third block will have the balance of the body of the rug and the two side strips which connect the end 40 border. The cams are arranged so that the blocks can print independently the right hand border, for instance, and while that surface is passing through the machine the other blocks will be held out of engagement 45 until their special portion of the fabric is printed, at which time their particular cams will actuate the mechanism so that the correct impression will be made.

In Figs. 3 and 8, I have shown three rods 50 24, 24^a and 24^b. The rod 24 terminates at the shaft 10, while the rod 24^a extends to the second shaft 10^a and the rod 24^b extends to the third shaft 10^b.

If a three color rug is to be printed it will 55 only take three cams and three rods. These rods, instead of terminating at the several shafts 10, 10^a and 10^b, may be continued to the other series, as illustrated in diagram, Fig. 9, so that the shafts 10, 10^a and 10^b will 60 be driven in unison and their several blocks will print at the same time—one block printing one color and another block printing a different color, but the space printed by the block controlled by the shaft 10^a will not be 65 printed upon again until it is directly in line

with the block controlled by the shaft 10^b and then not again until in line with the block controlled by the shaft 10. This scheme can be carried out in any number of colors, according to the length of the machine to which the invention is applied.

I claim:—

1. The combination in a block printing machine, of a frame; a series of reciprocating block carriers; transverse shafts for 70 actuating the carriers; a driving shaft; clutch mechanism through which the transverse shafts are driven from the driving shaft; and automatic means for controlling the clutches so that certain of the shafts 80 can be driven while others remain stationary.

2. The combination in a block printing machine, of a frame; a series of reciprocating block carriers; a shaft for each block 85 carrier; a cam on the shaft for actuating the carriers; a driving shaft; clutch mechanism at each cam shaft through which the said shafts are driven from the main shaft; a series of cams; and means connecting each 90 cam with a given clutch mechanism so that, as the cams rotate, certain of the clutches will be released while others will be in engagement so that certain of the carriers will 95 be out of action while others are printing.

3. The combination in a block printing machine, of a reciprocating carrier for a printing block; a transverse shaft; a cam on the shaft for actuating the carrier; a worm wheel loose on the shaft; means for driving the worm wheel; a clutch head secured to the shaft and carrying a bolt arranged to be projected into an opening in the worm wheel so as to cause the shaft to turn with the worm wheel; a retractor for the bolt arranged to engage the bolt; and means for actuating the retractor.

4. The combination in a block printing machine, of a reciprocating carrier for a printing block; a transverse shaft; a cam on the shaft for actuating the carrier; a worm wheel loose on the shaft; means for driving the worm wheel; a clutch head secured to the shaft and carrying a bolt arranged to be projected into an opening in the worm wheel so as to cause the shaft to turn the worm wheel; a retractor for the bolt arranged to engage the bolt; means for actuating the retractor; a rod carrying the retractor; and a cam for actuating the rod so as to move the retractor into and out of position.

5. The combination in a block printing machine, of a series of carriers for the blocks; a transverse shaft for each carrier; a cam at each end of each shaft arranged to lift the carriers; a longitudinal driving shaft having a worm at each transverse shaft; a worm wheel loose on each shaft and meshing with its worm; a clutch on each 125

130

shaft arranged to engage the worm wheel; a driven shaft having a series of cams thereon; a rod for each cam; and means carried by the rod for actuating the clutches so that certain clutches can be released as dictated by the cams.

6. The combination in a block printing machine, of a series of block carriers; a cam shaft for each block carrier; a cam thereon for actuating its carrier; a driven shaft; clutch mechanism between the driven shaft and each cam shaft; means for actuating the several clutch mechanisms including the

cam, the latter cams being so arranged with respect to the cam for raising the block carriers that the clutch mechanism will be thrown out of action when the block carrier is in the elevated position. 15

In testimony whereof, I have signed my name to this specification, in the presence of 20 two subscribing witnesses.
